United States Patent Office.

GEORGE A. SEAVER, OF NEW YORK, N. Y.

Letters Patent No. 84,382, dated November 24, 1868.

IMPROVEMENT IN REVERSIBLE LATCHES.

The Schedule referred to in these Letters Patent and making part of the same.

To all whom it may concern:

Be it known that I, GEORGE A. SEAVER, of New York, in the county and State of New York, have invented a certain new and useful Improvement in Reversible Locks; and I do hereby declare that the following is a full, clear, and exact description of the same, reference being had to the accompanying drawing, making a part of this specification, and to the letters of reference marked thereon.

My invention relates to that class of locks that are made with reversible latches, so that a single lock may be used, either right or left.

It consists in making the tail that carries the latch of a flexible plate, which also carries the follower, in such a manner that the latter, or the pair of followers, which I prefer to use, one for each side plate of the lock, may be compressed together inside the case, on the removal of the spindle, so that the latch may be drawn forward through its plate until its cylindrical neck corresponds with the square opening of the plate, when it may be turned in its tail-piece, to operate either right or left, and then replaced in the case, with the followers in their proper position for the reception of the spindle. To insure the return of the followers after they have been drawn forward, they are furnished with an appropriate spring.

To enable others skilled in the arts to which it appertains, to make and use my invention, I will proceed to describe its construction and operation, with reference to the drawing.

Figure 1 is an elevation, in section, of that portion of a lock occupied by the latch-mechanism;

Figure 2 is a horizontal section of the same;

Figure 3 is also a horizontal section, with the followers collapsed and drawn forward within the case, and the latch projecting and reversed.

The latch *a* has a cylindrical collar, *b*, and is riveted so that it will turn in the tail-piece *c*, to which it is secured.

The tail-piece *c* is a flexible plate that carries a pair of followers, *d d*, one on each side, each of which is held by the fitting of the edges of a slot in the tail-piece into a groove of the follower.

The ends of the slots opposite those at which the followers are carried are made large enough to admit the collars of the followers, so that the latter may be inserted into the slots and then moved into their proper position, with the edges of the slots fitting into the grooves, where they are held by the action of the spring *e*.

In ordinary use, the lock operates in the ordinary way.

The spindle *f* turns the followers *d*, and draws back the tail of the latch, so that the latter is withdrawn from the striking-plate on the jamb of the door.

On releasing the handle, the latch is thrown forward by the spring *g*.

When it is desired to reverse the action of the latch, the spindle is removed, the followers pressed within the case, and the latch, tail-piece, and followers drawn forward until the cylindrical collar of the latch projects through the case of the lock, as drawn in fig. 3, when the latch may be turned and the whole replaced within the case, the spring *e* insuring the passage of the followers back to their proper position for the reception of the spindle.

The details of the arrangement of the springs, and the construction of the tail-piece of the latch, and its combination with the follower or followers, may be varied, without departure from the principle of the invention, but I prefer that it should be carried into effect substantially in the manner illustrated in the drawings.

I claim the flexible tail-piece *c*, constructed and arranged substantially as described, and for the purpose specified.

And I also claim, in combination with a reversible latch and flexible tail-piece, the application of the spring *e*, for the return of movable followers to their proper position.

G. A. SEAVER.
